[57] **CLAIM**

The ornamental design for a valgus big toe rectifying supporter, as shown and described.

DESCRIPTION

FIG. 1 is a front top perspective view of a valgus big toe rectifying supporter showing my new design;

FIG. 2 is a rear bottom perspective view thereof;

FIG. 3 is a top plan view thereof, the broken line showing of the foot is for illustrative purposes only and forms no part of the claimed design; and,

FIG. 4 is a front top perspective view of a second embodiment thereof, being the same in appearance as that shown in FIGS. 1-3 except for the formation of two pieces of cloth partially seamed with each other.

FIG. 1

FIG. 2

FIG. 3**FIG. 4**
